UNITED STATES PATENT OFFICE

NATHAN WEIDNER, OF NEW YORK, N. Y., ASSIGNOR TO VANTILITIES, INC., OF NEW YORK, N. Y., A CORPORATION OF NEW YORK

DESIGN FOR A COMBINATION POWDER COMPACT, LIP STICK, AND ATOMIZER

Application filed May 28, 1930. Serial No. 35,799. Term of patent 7 years.

To all whom it may concern:

Be it known that I, NATHAN WEIDNER, a citizen of the United States, residing at New York city, county of Bronx, borough of Bronx, and State of New York, have invented a new, original, and ornamental Design for a Combination Powder Compact, Lip Stick, and Atomizer, of which the following is a specification, reference being had to the accompanying drawing, forming a part thereof.

I claim:—

The ornamental design for a combination powder compact, lip stick and atomizer, as shown.

NATHAN WEIDNER.
